UNITED STATES PATENT OFFICE.

HENRY M. WOLFSON, OF NEW YORK, N. Y.

VARIABLE CONDENSER.

Application filed June 19, 1922. Serial No. 569,272.

To all whom it may concern:

Be it known that I, HENRY M. WOLFSON, a citizen of the United States, residing at 488 East 140th Street, New York, in the county of Bronx and State of New York, have invented certain new and useful Improvements in Variable Condensers, of which the following is a specification.

My invention relates to a new and improved form of variable condenser.

One of the objects of my invention is to provide a variable condenser of a simple and strong construction, which can be readily manufactured and assembled.

Another object of my invention is to provide a variable condenser which although of simple construction can be delicately regulated.

Another object of my invention is to provide a variable condenser especially adapted for use in radio receiving circuits.

Other objects of my invention will be set forth in the following description and drawings which illustrate a preferred embodiment thereof.

Fig. 1 is a side elevation partially in section.

Fig. 2 is a section on the line 2—2 of Fig. 1.

Fig. 3 is a section on the line 3—3 of Fig. 1.

Fig. 4 is a bottom perspective view of the stator.

Fig. 5 is a perspective view of the rotor.

Fig. 6 is a perspective view of one of the rotor plates, and Fig. 7 of a stator plate.

In devices heretofore used it has been customary to have a stationary part which may be called the stator having a series of separated plates between which plates mounted upon a movable shaft, and forming what may be called a rotor could be caused to enter to a greater or less extent. However, the regulation that could be accomplished by revolving the shaft of the rotor was clearly not sufficient for fine tuning and it was necessary to provide reducing gears or the like in order to be able to revolve the shaft of the rotor to only a slight extent. This, of course, added considerably to the complication and cost of manufacture of the article.

According to my invention the stator and

rotor plates are respectively arranged in what may be called a helical arrangement so that the plates of the rotor enter one by one between the plates of the stator and a very delicate regulation can be secured.

As clearly shown in Figs. 1 and 3, a plate 1 which can be made of any suitable insulating material has four posts R secured thereto by means of the nuts 12. As clearly shown in the left hand side of Fig. 1, each said post has a shank of reduced width which can pass through a hole of corresponding size in the plate 1 and this shank can be engaged by the nut 12. The stator plates 4 have the form shown in Fig. 7 and have a shape substantially like a quadrant of a disc having an inner arcuate end. These stator plates 4 have orifices 5. As clearly shown in Figs. 3 and 7, the holes 5 are of such size that each plate 4 can be slipped upon two of the said rods R with its arcuate inner end adjacent the central part of the device.

Sleeve-like spacing members 2, 2', 3 and 3' are provided for holding the said stator plates 4 and in properly spaced position and the stator plates and said sleeve members are tightly pressed together by means of the nuts 6 which cooperate with the threaded bottoms of the posts R. By reason of this construction the parts can be readily manufactured and quickly and efficiently assembled.

The rotor consists of an externally threaded shaft 9 having index disc 14 and a knurled head 15 secured thereto. As clearly shown in Fig. 6 each rotor plate 17 has an orifice 18, a downward tongue 19 and a recess 20. It is also clear that each rotor plate 17 also has the general shape of a quadrant of a disc. The consecutive plates 17 of the rotor occupy consecutive quadrants as shown in Fig. 5 with the tongue 19 of each upper plate 17 fitting into the recess 20 of the adjacent lower plate. This is also clearly shown in Fig. 2.

The orifice 18 of each rotor plate 17 is of sufficient diameter to enable the said plate to be slipped over the bolt-like extension 9' of the shaft 9. As can be clearly seen in Figs. 2 and 5 a series of sleeves 21 serve to keep the respective rotor plates 17 in proper vertical relationship and the sleeve 21 and rotor plates 17 are firmly clamped into position by

means of the nut 22 located at the threaded bottom of the extension 9'. Hence the completely assembled rotor has its plates 17 firmly locked against all vertical movement and 5 against all transverse movement. Before the indicator or index disc 14 and the head 15 are secured to the shaft 9, the top of the said shaft can be passed above the top stator plate 4 and through the central opening in 10 the disc 1. This central opening is threaded and an external bushing 7 can be secured in the said opening and this can be firmly held in position by means of the nut 8. The outer bushing 7 has its central opening threaded 15 so that an externally threaded inner bushing 10 can be adjustably secured in position. The opening of the said inner bushing 10 is also threaded so that it can cooperate with the external thread of the shaft 9. By 20 revolving the inner bushing 10 so that it moves up and down in the outer bushing 7 the shaft 9 may be vertically adjusted without revolving it. This is to insure the proper relative position of the topmost rotor plate 25 17 with respect to the bottom stator plate 4 so that the rotor plates can move between the stator plates and also upwardly so that the rotor plates and the stator plates have a relation similar to the cooperating threading 30 of a nut and the bolt.

The inner bushing 10' has an upper part without any threading and of a reduced diameter and this can be engaged by means of the set screw 11 so as to firmly lock the inner 35 bushing 10 without injuring any part of the threading thereof.

When the parts are thus assembled, the index disc 14 and the knurled head 15 can be secured to the shaft 9 by any suitable 40 means so that these parts 14 and 15 can be preferably detached from the shaft 9. When the head 15 is now turned this causes the shaft 9 to revolve so that each rotor plate 45 has a helical motion whereby it passes between the stator plates and also moves upwardly so as to pass between successive pairs of the stator plates. It is obvious that as the shaft 9 is further revolved that more of the rotor plates 17 pass between the stator plates 50 4, so that the capacity of the condenser is very delicately and gradually increased by a relatively large revolution of the shaft 9.

A suitable index 16 is preferably secured to the plate 1 so that it cooperates with the 55 index disc 14 to indicate the capacity of the condenser.

I have shown a preferred embodiment of my improved condenser and of my improved method for bringing the rotor plates and 60 stator plates into the operative position but it is obvious that numerous omissions and changes could be made without departing from the spirit of my invention.

Wherever the parts are referred to either 65 in the description or in the claims by numer-

als, my invention is not to be limited to the form shown in the preferred embodiment herein illustrated.

It is obvious that the stator and rotor plates are held in spaced vertical relation, 70 and also in spaced angular relation. By the latter phrase I mean that they are not superposed and that in passing from one to the other it is necessary to perform angular movement about the vertical axis if the condenser is so held that its axis is vertical. Of course, the operation of my condenser is the same, no matter how the axis thereof is held. 75

It is obvious that if desired, the series of 80 plates of the stator could be joined to form a continuous helical winding similar to the internal thread of a nut. Correspondingly, the series of plates of the rotor could be joined to form a similar helical winding, 85 like the threading of a bolt. Such structures are obvious equivalents for the one illustrated in the embodiment before described. Such parts could be cheaply made by a single casting. 90

The series of stator plates are equivalent to and may be referred to as stator plate means, and the series of rotor plates may be similarly referred to as rotor plate means. I believe that I am the first to provide a 95 condenser whereby the capacity is varied by a simultaneous vertical and horizontal movement of the rotor plate means with respect to the stator plate means. 100

I claim:

1. A condenser having a plurality of helically arranged and stationary plates and a plurality of movable plates arranged in like helical arrangement, and means for rotating and vertically moving said movable plates adapted to successively introduce them between said stationary plates. 105

2. A condenser having a series of substantially quadrantal stationary plates which are vertically spaced from each other and occupy successive quadrants, a series of quadrantal movable plates similarly arranged, and means for rotating and vertically moving said movable plates adapted to cause them to successively pass between said stationary plates. 110

3. In a condenser, a threaded shaft having an extension threaded at its bottom, a series of plates each having a recess and each having a tongue engaging the recess of the adjacent plate, each said plate having an orifice whereby it can be mounted on said extension, spacing sleeves mounted on said extension between said plates which are mounted on said extension, and a nut adapted to clamp said plates and spacing members together. 115

4. A condenser having a stationary part provided with stator plate means, a revoluble shaft having rotor plate means mounted 120

thereon and spaced from said stator plate varied, the said revoluble shaft having a means, and means adapted to cause such simultaneous revolution of said shaft and such longitudinal movement thereon, that said 5 rotor plate means and said stator plate means remain spaced from each other and the length of said rotor plate means interposed between said stator plate means is

free longitudinal movement with respect to 10 said stationary part which exceeds the distance between said stator plate means and said rotor plate means.

In testimony whereof I hereunto affix my signature.

HENRY M. WOLFSON.
